UNITED STATES PATENT OFFICE.

CHARLES F. MILLER, OF MOORE, PENNSYLVANIA, ASSIGNOR TO WESTINGHOUSE ELECTRIC & MANUFACTURING COMPANY, A CORPORATION OF PENNSYLVANIA.

METHOD OF AND APPARATUS FOR BURNING PULVERIZED FUEL.

Application filed September 16, 1921. Serial No. 501,011.

To all whom it may concern:

Be it known that I, CHARLES F. MILLER, a citizen of the United States, and a resident of Moore, in the county of Delaware and 5 State of Pennsylvania, have invented a new and useful Improvement in Methods of and Apparatus for Burning Pulverized Fuel, of which the following is a specification:

My invention relates to a furnace for 10 burning powdered fuel and it has for an object the provision of an improved method and apparatus of the character designated in which the solid ash-dust particles shall be to a large extent separated within the fire box 15 from the gaseous products of combustion in order that a minimum amount of ash-dust shall be carried from the fire box with the products of combustion and shall find lodgment upon the tubes of the boiler, in the 20 draft flues or stack leading therefrom, or shall be discharged from the stack into the atmosphere.

In the accompanying drawings, Fig. 1 is a longitudinal view, partially in section 25 and partially in elevation, of a conventional water tube boiler equipped with my improved pulverized-fuel burning furnace; Fig. 2 is a fragmentary transverse sectional view of the furnace illustrated in Fig. 1; 30 and Figs. 3, 4, and 5, are fragmentary longitudinal sectional views of modified constructions of the pulverized-fuel burning furnace illustrated in Fig. 1.

In steam generator installations equipped 35 with pulverized-fuel burning furnaces as heretofore constructed, considerable difficulty has been experienced in securing an efficient rate of heat transfer from the combustion gases to the boiler heating surfaces because of the high percentage of ash-dust 40 which is carried along with the combustion products into the boiler and which settles upon the boiler heating surfaces forming a heat insulating coating thereupon. Further 45 difficulties in such furnaces have arisen because of the large quantities of ash-dust settling in the flue connections and in the chimney which must be removed therefrom at frequent intervals, thus increasing the expense 50 of operation of the steam generator and decreasing the efficiency of its operation during such periods because of the inrush of air into the draft passages and stack. Further-

more, the discharge of dust from the chimney is objectionable, especially in cities. 55

The purpose of my present invention is to burn pulverized fuel in such manner as to largely separate the ash particles from the gaseous products of combustion prior to the entry of the furnace gases into the boiler proper. This I accomplish by bringing the flame resulting from the burning of a mixture of pulverized fuel and air into a direct and intimate contact with a surface coating of molten slag and by causing the flame further to spread and eddy against other slag-coated surfaces, in order to cause the fine troublesome particles of ash-dust to adhere to and become fused in the molten slag surfaces. 70

In carrying out my invention I introduce the mixed fuel and air for combustion into the fire box of the furnace in the form of a thin sheet, substantially horizontal or tangential to the slag surfaces, thereby causing 75 the whole molten slag surface to be covered with a thin film of flame, insuring a greater surface contact between the flame and the slag surface and a more complete separation of the dust particles from the gaseous products of combustion. Moreover this method of combustion in which the flame impinges 80 against the slag-coated surfaces serves in a large measure to protect the brick work of the furnace fire box from the erosion commonly caused by the impingement of the 85 flame upon the fire box wall.

Referring to the drawing for a more detailed understanding of an apparatus, I indicate in Figure 1 a boiler plant in which the numeral 10 designates generally the boiler construction, which may be of any well-known type, the present invention being in no wise limited to a use with any specific design of boiler. Located beneath 90 the front end of the boiler is the fire box 11 which may be constructed of refractory material, as is the usual practice in furnace construction. Beneath the rear end of the boiler is the usual settling chamber 12. A 95 slag refuse chamber 13 having the usual clean-out closure 14 and communicating therethrough with a suitable pit 15 is disposed beneath the fire box in such manner as to receive ash and slag from the fire box. 100 The fire box 11 comprises a front wall 16,

side walls 17, a rear bridge wall 18 and a bottom wall 19, the latter having its upper exposed surface lying in a plane slightly inclined to the horizontal and having an upwardly extending dam 20 at its rear end, the top of the dam being substantially at the same level as the elevated front end of the bottom wall 19.

Disposed in the front walls 16 and adjacent the upper surface of the bottom wall 19 are a plurality of horizontally aligned nozzles 21. The nozzles 21 are circular in cross section at their outer extremities and are flattened and downwardly declined toward the inner extremities, the arrangement being such that the several nozzles deliver into the furnace a thin sheet of mixed pulverized fuel and air at a slight inclination to the horizontal. Each of the several nozzles is suitably connected by a nipple 22 with a manifold 23 which receives the mixed pulverized fuel and air through a conduit 24 leading from a conventional mechanism 25 for pulverizing the fuel and mixing the pulverized fuel with air. The constructional characteristics of the mechanism 25 form no part of my present invention and hence a detailed description thereof is deemed unnecessary in the present application.

The inclined upper surface of the bottom wall 19 cooperates with the dam 20 at the rear end thereof to form a shallow basin 26 which I preferably fill with a fusible slag. The top and rear walls of the dam 20 and at least a lower portion 27 of the bridge wall 18 are also preferably coated with slag to protect the walls from the erosive action of the flame and to catch the dust particles as is hereinafter more fully described. One or more vertically disposed openings 28 extending from the fire box 11 at the rear of the dam 20 and opening into the slag pit 13 are provided for the withdrawal of excess slag and ash from the fire box.

The manner in which my improved pulverized-fuel burning furnace operates is clear from the above description. In brief, the commingled pulverized fuel and air is delivered at a considerable pressure through the conduit 24 to the manifold 23, thence distributed to the several nozzles 21 from which the mixed fuel and air is discharged into the fire box 11 in a thin sheet horizontal with respect to the front wall of the furnace. Combustion ensues upon the admission of the mixed fuel and air into the furnace and the resulting thin sheet of flame is directed so as to impinge at a slight angle against the surface of the molten slag within the basin formed by the dam 20. The flame plays over substantially the entire surface of the slag, which is consequently maintained in a molten condition, so that the solid dust particles readily ad-

here to and become fused in the heated slag and any unburned particles caught in the molten slag are maintained at a high temperature until they have been completely consumed. The flame slides along the surface of the molten slag and impinges against the bridge wall 18 against which the flame spreads and eddies, causing dust particles still held in suspension in the flame to adhere to and become fused with the slag coating on the bridge wall 18.

It is evident that this direct and intimate contact of the flame with the slag-coated surfaces which is successively repeated by bringing the flame into the direct intimate contact with other slag-coated surfaces serves to effect the separation of a large percentage of the ash-dust from the combustion gases before these gases are delivered through the upper portion of the fire box 11 to contact with the heating surfaces of the boiler 10.

The construction disclosed in Fig. 3 is similar to that illustrated in Figure 1. The relation of the walls 16, 17, 18 of the fire box are identical with that disclosed in Figure 1. The bottom wall 30 however, is constructed to afford a greater slag-coated surface subjected to eddying currents of the thin sheet of flame. As shown, the bottom wall 30 is provided with an inclined upper surface 31 adjacent the front of the furnace, an intermediately disposed dam 32, and an inclined surface 33 at the rear of the dam 32 at a considerably lower level than the surface 31. This construction serves to provide a shallow pool 34 which is filled with slag and against which the flame discharged from the nozzles 21 impinges. In addition, the flame is caused to spread and eddy against the slag-coated surface 35 on the lower portion of the bridge wall 18, the slag-coated surface of the rear wall of the dam 32, and the inclined surface 33. The operation of the furnace above described is in every respect similar to that recited in relation to the furnace illustrated in Figure 1, the construction differing only in that the slag-coated surface against which the flame from the nozzles directly impinges is decreased in extent and the slag-coated surface against which the flame is brought into eddying contact is increased in extent.

The construction illustrated in Figure 4 differs from the constructions heretofore described in that the slag-coated surfaces to which the eddying portion of the flame are brought into contact are arranged at a higher level than the slag-coated surfaces against which the flame directly impinges and in a stepped relation thereto in such manner that the excess slag flows downwardly over the stepped surfaces so as to be discharged at the front of the furnace into the slag pit. As shown, the front and side walls 16 and

17 of the fire box and the nozzles 21 in the front wall thereof, are in all respects identical with the construction described in connection with Figure 1. The bottom wall 40 5 of the fire box comprises a horizontally disposed portion 41 which is spaced at one or more points from the front wall 16 to form the slag discharge openings 42. The rear portion of the bottom wall 40 comprises a 10 series of sinuate steps rising from the upper surface of the front portion 41 and extending into the bridge wall 18. Rising from the top of the series of steps 42 a portion 43 of the bridge 18 overhangs the steps 42, 15 which portion 42 may also present a plurality of vertically stepped surfaces against which the flame may eddy. In operation, the thin sheet of flame from the nozzles 21 impinges at a slight angle upon the molten 20 slag on the bottom wall portion 41 and is deflected upwardly into eddying contact with the slag-coated surfaces upon the series of steps 42 and upon the overhanging portion 43 of the bridge wall 18. The dust particles 25 adhere to the slag and the excess slag collecting upon the walls of the fire box flows downwardly and forwardly across the portion 41 of the bottom wall through the openings 42 into the slag pit 13.

30 The modification of my apparatus illustrated in Figure 5 comprises an arrangement of slag-coated surfaces in which the flame is caused to eddy downwardly against slag-coated surfaces and in which provision 35 is also made for bringing the upwardly eddying flame into intimate contact with slag-coated surfaces. In this embodiment, a bottom wall 50 is provided with a slightly inclined portion 51 adjacent the front wall 16 40 of the furnace which cooperates with a dam 52 at an intermediate portion of the bottom wall 50 to form a shallow basin 53 for containing molten slag. The rear portion of the bottom wall 50 comprises a series of 45 sinuate steps 54 at the rear of which are one or more openings 55 leading into the slag pit 13. The bridge wall 18 is constructed to overhang the rear portion of the fire box, the overhanging portion being 50 preferably serrated as shown at 56, as in the construction illustrated in Figure 4 heretofore described. The bottom wall 50 and at least the lower portion of the bridge wall 18, including the serrated overhanging 55 portion 56, are coated with a suitable slag. The sheet of flame issuing from the nozzles 21 first impinges against the slag in the shallow basin 53 to which some of the solid ash particles adhere and is deflected in a 60 substantially horizontal flame toward the rear of the fire box. The descending step portion 54 of the bottom wall induces downwardly eddying currents of the burning gases which intimately contact with the 65 slag-coated surface of the step portion 54.

The bridge wall 18 serves to spread the flame and the overhanging portions to deflect the upwardly eddying combustion products so as to further remove the ash particles therefrom.

70 It is evident from the above description that the essence of my invention resides in the introduction into the fire box of a furnace of a thin sheet of mixed powdered fuel and air in such manner as to produce a resulting thin sheet of flame, in bringing the flame into direct and intimate contact with a surface of molten slag, and in causing the flame deflected from the slag surface to spread and eddy against other slag-coated 75 surfaces so as to remove the ash-dust particles from the gaseous products of combustion. The invention is then essentially a method of and apparatus for burning powdered fuel and separating the solid from the 80 gaseous products of combustion, and obviously may be carried out within furnaces of varied construction.

85 While I have shown my invention in several forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended 90 claims.

95 What I claim is:-

100 1. The method of burning comminuted fuel which comprises forcefully discharging a thin sheet of intimately mixed comminuted fuel and air into a furnace in a substantially horizontal plane, causing a combustion of the mixed fuel and air upon 105 their entry into the furnace, and directing the resulting thin film of flame along the horizontally disposed surface of a layer of molten slag.

110 2. The method of burning comminuted fuel which comprises forcefully discharging a thin sheet of intimately mixed comminuted fuel and air into a furnace in a plane slightly inclined to the horizontal, causing a combustion of the mixed fuel and air upon 115 their entry into the furnace, and directing the resulting thin film of flame along the horizontally disposed surface of a layer of molten slag.

120 3. The method of burning comminuted fuel which comprises forcefully discharging a thin sheet of intimately mixed comminuted fuel and air into a furnace in a substantially horizontal plane, causing a combustion of the mixed fuel and air upon 125 their entry into the furnace, directing the resulting thin film of flame along the horizontally disposed surface of a layer of molten slag and then causing the horizontally projected flame to change its direction 130

of travel whereby upon the change of direction of the flame solid products of combustion are separated from the combustion gases.

- 5 4. The method of burning comminuted fuel which comprises forcefully discharging a thin sheet of intimately mixed comminuted fuel and air into a furnace in a substantially horizontal plane, causing a 10 combustion of the mixed fuel and air upon their entry into the furnace, maintaining a temperature within the furnace sufficient to fuse the solid products of combustion, and directing the thin film of flame along 15 the horizontally disposed surface of a body of molten slag formed by the accretion of fused products of combustion.

5. In the art of burning comminuted fuel in a furnace provided with a substantially 20 plane surface upon which a layer of molten slag may slowly flow to a slag pit, the method which comprises forcefully discharging a thin sheet of intimately mixed comminuted fuel and air into the furnace 25 in a plane approximate to that of a surface of the furnace coated with slag formed by the accretion of fused products of combustion, causing a combustion of the mixed fuel and air upon their entry into the furnace, directing the resulting thin film of flame along slagged surface and continuously withdrawing excess slag.

6. In combination in a furnace for burning comminuted fuel, a fire box, means for 30 forcefully injecting into the fire box a thin sheet of intimately mixed comminuted fuel and air to effect upon combustion a forwardly moving thin film of flame, said fire box having a wall member covered with 40 slag the surface of which is so disposed as to lie approximately in the plane in which the sheet of flame is projected, whereby the thin film of flame engages and sweeps along the slagged surface.

45 7. In combination in a furnace for burning comminuted fuel, a fire box having a wall upon which the fused products of combustion collect in the form of molten slag, means for forcefully injecting into the fire 50 box a thin sheet of intimately mixed comminuted fuel and air in such manner as to effect upon combustion a forwardly moving thin film of flame, said injecting means and said wall being so disposed relatively 55 to one to the other that the film of flame is projected along the slagged surface of the wall.

8. In combination in a furnace for burning 60 comminuted fuel, a fire box having a wall upon which the fused products of combustion collect in the form of molten slag, means for forcefully injecting into the fire box a thin sheet of intimately mixed comminuted fuel and air in such manner as to 65 effect upon combustion a substantially rec-

tilinearly moving film of flame, said wall being so disposed that its slagged surface is contiguous to the rectilinear path of travel of the flame and is thereby enveloped by the flame.

9. In combination in a furnace for burning comminuted fuel, a fire box having a wall upon which the fused products of combustion collect in the form of molten slag, means for forcefully injecting into the fire 75 box a thin sheet of intimately mixed comminuted fuel and air in such manner as to effect upon combustion a forwardly moving thin film of flame, said injecting means and said wall being so disposed relatively to each other that the forwardly moving film of flame impinges upon the slagged surface at such small angles as to cause the flame to travel in contact with the slagged surface of said wall with substantially no deflection 80 therefrom during the early stages of combustion.

10. In combination in a furnace for burning comminuted fuel, a fire box having a wall upon which the fused products of combustion collect in the form of molten slag, means for forcefully injecting into the fire box a thin sheet of intimately mixed comminuted fuel and air in such manner as to effect upon combustion a forwardly moving thin film of flame, said injecting means and said wall being so disposed relatively to each other that the forwardly moving film of flame impinges upon the slagged surface at such small angles as to cause the flame to travel in contact with the slagged surface of said wall with substantially no deflection 90 therefrom during the early stages of combustion, and a second furnace wall so disposed with respect to the forwardly moving film of flame as to cause a marked change in the direction of the travel of the flame 95 whereby the solid products of combustion are largely separated from the gaseous products of combustion.

11. In combination in a furnace for burning comminuted fuel, a fire box having a wall upon which the fused products of combustion collect and present a substantially horizontally exposed surface of molten slag, 105 means for forcefully injecting into the fire box a thin sheet of intimately mixed comminuted fuel and air in such manner as to effect upon combustion a forwardly moving thin film of flame, said injecting means being so disposed with respect to the wall that the forwardly moving film of flame envelops the exposed surface of slag with substantially no deflection therefrom.

12. In combination in a furnace for burning comminuted fuel, a fire box having a wall upon which the fused products of combustion collect and present a substantially horizontally exposed surface of molten slag, 115 horizontally aligned nozzles in the front 120

wall of the fire box for forcefully injecting into the fire box a thin sheet of intimately mixed comminuted fuel and air and so disposed that a substantially horizontal film of flame travels along and envelops the exposed slag surface.

13. In combination in a furnace for burning comminuted fuel, a fire box having a wall upon which the fused products of combustion collect and present a substantially horizontally exposed surface of molten slag, means for forcefully injecting into the fire box a thin sheet of intimately mixed comminuted fuel and air in such manner as to effect upon combustion a forwardly moving thin film of flame, said injecting means being so disposed with respect to the wall that the forwardly moving film of flame envelops the exposed surface of slag with substantially no deflection therefrom, and means for abruptly deflecting said sheet of flame after its passage beyond said horizontal slagged surface.

14. In combination in a furnace for burning comminuted fuel, a fire box having a wall upon which the fused products of combustion collect and present a substantially horizontally exposed surface of molten slag, means for forcefully injecting into the fire box a thin sheet of intimately mixed comminuted fuel and air in such manner as to effect upon combustion a forwardly moving

thin film of flame, said injecting means being so disposed with respect to the wall that the forwardly moving film of flame envelops the exposed surface of slag with substantially no deflection therefrom, and wall means for reversing the direction of travel of said flame after its passage beyond said horizontal slagged surface. 35

15. In combination in a furnace for burning comminuted fuel, a fire box having a wall upon which the fused products of combustion collect and present a substantially horizontally exposed surface of molten slag, means for forcefully injecting into the fire box a thin sheet of intimately mixed comminuted fuel and air in such manner as to effect upon combustion a forwardly moving thin film of flame, said injecting means being so disposed with respect to the wall that the forwardly moving film of flame envelops the exposed surface of slag with substantially no deflection therefrom, means for abruptly deflecting said sheet of flame after its passage beyond said horizontal slagged surface, 40 45
